UNITED STATES PATENT OFFICE.

HARRY R. WAIT, OF BUFFALO, NEW YORK.

DEVICE FOR REMOVING THE CLOSURE-BOARDS OF GRAIN-CAR DOORS.

1,376,124.

Specification of Letters Patent. Patented Apr. 26, 1921.

Application filed January 9, 1920. Serial No. 350,482.

To all whom it may concern:

Be it known that I, HARRY R. WAIT, a citizen of the United States, residing at Buffalo, in the county of Erie and State of New York, have invented a new and useful Improvement in Devices for Removing the Closure-Boards of Grain-Car Doors, of which the following is a specification.

This invention relates to devices for opening or breaking in the door closures or coverage of grain cars. More particularly the invention relates to devices of this sort which are automatically operated, and which have a ram or member adapted to engage the boards and force them inwardly off of the door frame.

One object of the invention is to provide a device of this sort which can be arranged vertically in a grain receiving pit at the side of the railway track so that it will occupy the minimum amount of horizontal or track space, thus enabling, if desired, two of the devices to be arranged between two railway tracks and operated to open two cars on the tracks at the same time.

Another object is to so construct the device that, if desired, it can be arranged in a grain-receiving pit in which one or more car unloading apparatus is or are installed, and can be operated by the same kind of power taken from the same source.

Another object is to provide a device of this sort with a power-actuated piston which moves up and down, and is attached to a door-opening member which is adapted to swing downwardly and outwardly from an upright inoperative position to a lateral operative position in contact with the car door.

Another object is to provide the device with novel means for adjusting the operative position of the door opening member, to cause it to properly engage the doors on different cars notwithstanding variations in the width of the cars or the height of their floors or door sills.

Other objects are to simplify and improve devices of this sort in the respects herein-after set forth and claimed.

In the accompanying drawings:

Figure 1 is a longitudinal vertical sectional elevation of a car door-opening device embodying the invention, showing the parts in full lines in its inoperative position, and showing in dotted lines an intermediate position.

Fig. 2 is a side elevation thereof, showing by full and broken lines, successive positions of the door opening member in engagement with the boards of the door.

Fig. 3 is a sectional plan view thereof on line 3—3, Fig. 2.

In the drawings, a door opening device is shown as being located with its operating mechanism standing upright in an unloading pit B, into which the grain is discharged from the cars, and which may be arranged to accommodate one or more car-unloading apparatus C, a portion of one of such apparatus being indicated by the rail c and beam c'. A preferred arrangement includes two car-unloading apparatus disposed in a single unloading pit in alignment with two sets of tracks, and a central partition D is provided, on opposite sides of which two of the door opening devices are arranged to work in opposite directions, so that if desired they may be simultaneously actuated to operate on two cars, one on each of the said unloading apparatus. Only one of the door opening devices is shown. A portion of one car is shown at E and the grain door, as usual comprises horizontal boards or planks e disposed at the inner side of and nailed or otherwise secured to the door frame e' so as to close the door opening e². A platform F is provided which is suitably supported over the partition D between the two tracks, and on which the operative can stand to observe and control the various operations of the door opening devices and car-unloading apparatus. Any suitable arrangement or relative disposition of these parts may be used, or the door-opening device or devices may be independently installed in a pit without the car-unloading apparatus, as it is structurally and operatively independent thereof.

The embodiment of the invention shown in the drawings is preferably constructed as follows:

A piston rod 10 and piston 10^a are arranged to reciprocate in an upright cylinder 11 which is preferably supported on the lower part of the partition D in the pit B. The pressure fluid for operating the piston 10^a may be of any suitable sort and from any suitable source, but is preferably of the same kind and from the same supply as used for the car-unloading apparatus.

The upper end of the piston rod 10 is provided with a crosshead 12 on which is

pivotally mounted a door opening member A, which is adapted to assume a substantially upright inoperative position above the pit B, when the piston 10^a is in its lowered position, and which as the piston rises, is adapted to swing outwardly and downwardly toward the car to engage the lower board e and push the same inwardly to detach it from the door frame. The continued upward movement of the piston will cause the door opening member to move laterally toward the car and on account of its form it will successively engage and detach a number of the door boards one after another until as many are removed as is necessary for the proper discharge of the grain.

The crosshead 12 preferably comprises a horizontal pivot shaft or rod 13, spacing sleeves 14, and rollers or wheels 15 journaled on the outer ends of the shaft 13 are adapted to engage the outer faces of fixed upright guide rails or abutments 16, which take the side thrust of the crosshead 12 when the door opening member A engages the door boards e, thus preventing bending or other injury to the piston rod 10.

The door opening member preferably comprises two upwardly-extending and laterally-bent or offset arms or bars 20, the lower ends of which are pivoted on the shaft 13. These arms are rigidly connected to each other by transverse bars or braces 21, and the outer ends of the arms are provided with shoes or plates 22 so spaced as to engage the boards e near their opposite ends, or adjacent the ends of the door frame e'. The shoes have curved or cam-shaped outer door-engaging edges or faces 23 which are so formed that when the door opening member is operated, the lower portions of the edges 23 will first engage the lowest board e and force it inwardly and successive portions of the edges 23 will then engage in succession and force off the other boards. The lower portions of the shoes 22 are rounded to form heels or projections 24, which are adapted to rest on the sill of the car to support the outer end of the door opening member.

The proportions and relative location of the various parts of the member A are such that when the piston rod 10 moves upwardly the member A will tend to fall or swing outwardly on its pivot 13 until the heels 24 rest on the door sill of the car. Then as the upward motion of the piston continues, the shoes rock on the heels so as to cause the curved edges 23 to engage the boards e at successively higher points, as will be apparent from Fig. 2.

Many of the grain cars in use vary in dimensions. Some are wider than others, and the sills or floors are lower in some cases than in others. It is therefore desirable that provision be made to properly sup-

port and guide the door opening member as it swings outwardly toward the car so that it will properly engage the lower board e, without striking the outer face of the sill, or engaging boards too high up. 70

The means preferably provided to accomplish this result are constructed as follows:

A transverse roller 25 is suitably journaled on the framework of the platform F or otherwise, adjacent the lower ends of the arms 20, said arms resting against the roller 25 in the lower position of the member A, and the member A is thus held upright as shown in Fig. 1. As the piston 10^a is raised to move the member A, the rollers 15 and crosshead 12 travel upwardly in a straight path on the guides 16, while the member A swings outwardly and downwardly by gravity over the roller 25, the arms 20 being supported by the roller 25. As the crosshead continues its upward movement the arms 20 will be carried out of engagement with the roller 25 and into engagement with another similar roller 27 located above the roller 25, and which is adapted to support the door opening member A and guide the heel thereof into proper engagement with the door sill of the car. The roller 27 is made adjustable to provide for varying horizontal and vertical positions of the sills on different cars. 85

The means shown in the drawings for adjusting the roller 27 comprise adjustable journal blocks 28 for the opposite ends of the shaft 26 arranged to slide on guides 29 on the platform frame. The journal blocks 28 are moved up and down by adjusting screws 30 swiveled in the guides 29 and engaging in threaded holes in the journal blocks. Hand wheels 31 or the like are provided for turning the screws. Any other suitable means may be provided for permitting the required adjustment of the roller 27. 100

In the construction shown in the drawings, shields or deflectors 35, 36 are provided for the purpose of preventing the grain from accumulating about and clogging the mechanism. These shields are preferably secured to and extend downwardly away from the partitions D, and the lower shield 36 is provided with an aperture through which the piston rod 10 extends. This shield surrounds the upper part of the cylinder 11. 105

I claim as my invention:—

1. In a device for removing grain car door boards, the combination with a door board removing shoe, of means for swinging said shoe into car door engaging position and rocking said shoe to force said boards from said door. 120
2. In a device for removing grain car door boards, the combination of a cylinder, a piston rod and a piston adapted to reciprocate in said cylinder, a ram member pivotally connected at one end to said piston 130

rod and having at its other end a cam-shaped edge, said ram member, when said piston rod moves in said cylinder, swinging on said pivotal connection to approach and engage successive door boards and remove them from the car door opening.

3. In a device for removing grain car door boards, the combination of a cylinder, a piston rod and a piston adapted to reciprocate in said cylinder, a roller journaled on the end of said piston rod, a guide for said roller disposed in parallel relation to the line of travel of said piston rod, a ram member one end of which is pivotally connected to said piston rod, a cam-shaped edge at the other end of said ram member, said ram member swinging on said pivotal connection to a position in which said cam edge will engage and remove the lowest door board as said piston moves outwardly in said cylinder and the continued outward movement of which causes said cam edge to engage and remove successive door boards.

4. In a device for removing grain car door boards, the combination of a ram member having a board-engaging shoe at one end thereof, a pivot at the opposite end of said ram member, and actuating means connected to said pivot to move the pivotally connected end of said ram in a straight path, said shoe moving at the same time in a curved path to a position in which it engages and removes the lowest door board and successively the required number of the remaining door boards.

5. In a device for removing grain car door boards, the combination of a cylinder, a piston rod and a piston adapted to reciprocate in said cylinder, a ram member pivotally connected at one end to said piston rod and having at its other end a cam-shaped edge, said ram member being adapted to assume an inoperative position substantially in alignment with said piston, a support adjacent said pivotal connection for supporting said member in said inoperative position, said ram member being adapted, when said piston is actuated, to swing on said pivot and rock on said support into a laterally extending operative position relative to said piston in which it will successively engage and remove the door boards.

6. In a device for removing grain car door boards the combination of a cylinder, a piston rod and a piston adapted to reciprocate in said cylinder, a ram member pivotally connected at one end to said piston rod and having at its other end a cam-shaped edge, said ram member being adapted to assume an inoperative position substantially in alignment with said piston, a support adjacent said pivotal connection for supporting said member in said inoperative position, said ram member being adapted, when said piston is actuated, to swing on said pivot

and rock on said support into a laterally extending operative position relative to said piston in which it will successively engage and remove the door boards, and means for supporting and guiding said ram member 70 during said swinging movement.

7. In a device for removing grain car door boards, the combination of a cylinder, a piston rod and a piston adapted to reciprocate in said cylinder, a ram member pivotally connected at one end to said piston rod and having at its other end a cam-shaped edge, said ram member being adapted to assume an inoperative position substantially in alignment with said piston, a support adjacent said pivotal connection for supporting said member in said inoperative position, said ram member being adapted, when said piston is actuated, to swing on said pivot and rock on said support into a laterally extending operative position relative to said piston in which it will successively engage and remove the door boards, and adjustable means for supporting and guiding said ram member during said swinging 80 movement, whereby said member will properly engage the door boards on cars of varying widths or floor heights.

8. In a device for removing grain car door boards, the combination of a ram member having a transversely disposed cam-shaped outer end edge, said ram member being arranged to swing from a substantially upright position to a laterally extending position in which said cam-shaped edge 95 will successively engage and remove the door boards, and actuating means for said ram member which cause the same to swing from said upright position to said laterally extending position.

9. In a device for removing grain car door boards, the combination of an actuating device movable along a substantially upright path, and a ram member pivoted to said actuating device to swing outwardly 110 when said actuating device is moved in said upright path, the outer end of said ram member being formed to successively engage and remove the door boards by the swinging movement of the ram member during 111 the continued movement of said actuating device.

10. In a device for removing grain car door boards, the combination of an actuating device movable along a substantially upright 120 path, and a ram member pivoted to said actuating device to swing outwardly when said actuating device is moved in said upright path, the outer end of said ram member being formed to successively engage and remove the door boards by the swinging movement of the ram member, and a support for normally retaining said ram member in a substantially upright position, said ram member being adapted, when said actu- 125 130

ating device is operated, to swing over said support into a laterally extending position relative to said actuating device and by the continued upward movement of said actuating device cause the outer end of said ram member to engage and remove the door boards successively.

11. In a device for removing grain car door boards, the combination of an actuating device movable along a substantially upright path, and a ram member pivoted to said actuating device to swing outwardly when said actuating device is moved in said upright path, the outer end of said ram member having a cam-shaped shoe with a heel portion at the lower end thereof adapted to rest on the door sill of the car, the inner end of said ram member, when said actuating device is operated, moving along said upright path, and the outer end of said ram member rocking on said heel to cause said shoe to engage and remove the door boards successively.

12. In a device for removing grain car door boards, the combination of an actuating device movable along a substantially upright path, and a ram member pivoted to said actuating device to swing outwardly when said actuating device is moved in said upright path, the outer end of said ram member having a cam-shaped shoe with a heel portion at the lower end thereof adapted to rest on the door sill of the car, the inner end of said ram member, when said actuating device is operated, moving along said upright path, and the outer end of said ram member rocking on said heel to cause said shoe to engage and remove the door boards successively, and adjustable means for guiding the outer end of said ram member during said swinging movement, to permit said heel to properly engage the sills of different cars in which the locations of the sills differ.

13. In a device for removing grain car

door boards, the combination of a substantially upright cylinder, and a piston and rod adapted to reciprocate therein, a roller journaled on the end of said piston, a substantially upright guide member for said roller, a ram member pivoted on said piston rod and having a cam-shaped shoe with a heel on the lower end thereof, said ram member when in its inoperative position being substantially in alinement with said piston, and when actuated, swinging in a curved path until said heel engages the car sill and said shoe contacts with the door boards, the continued upward movement of said piston causing a rocking movement of said shoe on said heel to successively engage and remove the boards of the door.

14. In a device for removing grain car door boards, the combination with a door board removing shoe, of means for swinging said shoe into engaging position with a portion of said shoe engaging one of said door boards and rocking said shoe upon its board engaging portion and for moving said shoe laterally whereby boards are forced inwardly and removed from said door.

15. In a device for removing grain car door boards, the combination of a cylinder, a piston rod and a piston adapted to reciprocate in said cylinder, an arm, a door board removing shoe on one end of said arm, a pivotal connection between the other end of said arm and said piston rod, whereby said arm is permitted to swing relatively to said piston rod and outwardly and downwardly and to car door engaging position, and adjustable means for limiting downwardly swinging movement of said arm.

Witness my hand this 6th day of January, 1920.

HARRY R. WAIT.
